UNITED STATES PATENT OFFICE.

JACOB S. SHERMAN, OF CHICAGO, ILLINOIS, ASSIGNOR TO UNIVERSAL LAMP CO., OF CHICAGO, ILLINOIS, A CORPORATION OF ILLINOIS.

ACETYLENE-GAS LAMP.

1,385,190.

Specification of Letters Patent. Patented July 19, 1921.

Application filed January 17, 1918. Serial No. 212,217.

To all whom it may concern:

Be it known that I, JACOB S. SHERMAN, a citizen of the United States, residing at Chicago, in the county of Cook and State 5 of Illinois, have invented certain new and useful Improvements in Acetylene-Gas Lamps, of which the following is a description.

My invention belongs to that general class 10 of gas lamps adapted for use as a miner's lamp, or as a bicycle, automobile, yacht lamp or the like, in which the lamp is composed of two parts, one of which constitutes a water chamber and the other positioned 15 below the water chamber is adapted to contain calcium carbid. Means are provided to deliver the water to the carbid, resulting in the generating of acetylene gas, which is thence conducted by a suitable duct to the 20 exterior of the lamp where it is provided with a suitable burner.

The object of my invention is to produce a lamp of this general character which shall be simple and economical in its construction 25 and effectual and satisfactory in its use.

To this end my invention consists in the novel construction, arrangement and combination of parts herein shown and described and more particularly pointed out 30 in the drawings.

In the drawings, wherein like reference characters indicate like or corresponding parts,

Figure 1 is a vertical section of my improved lamp illustrating the preferred form thereof;

Fig. 2 is a cross section of the water tube, valve-stem and guard on line 2—2 of Fig. 1;

Fig. 3 is an elevation of the preferred 40 form of guard.

Referring to the drawings, 1 represents a water chamber provided with a suitably capped inlet 2, whereby said chamber may be charged. In the preferred construction 45 shown in Fig. 1, this part is provided with a vertically extending tube 3, having a valve seat formed on the lower end thereof which depends from the upper chamber downward into the carbid chamber. The tube 3 is provided with openings 4 or equivalent means, by means of which the water may 50 find entrance therein, and is provided at its lower end with a valve 5 having a laterally extending top face adapted to seat against 55 the tube, and provided with a stem 6 which

is screw threaded as at 7 into the top of the water chamber. The numeral 8 designates the carbid chamber, which is constructed at its upper end with threads 9 adapted to coöperate with corresponding 60 threads 10 formed in the lower or depending part 11 of the water chamber. The numeral 12 designates a resilient guard or shield which in the preferred construction is formed of wire wound in substantially the 65 form of a helical spring with its free end tapered down and substantially closed. This guard is preferably soldered or otherwise operatively secured at its upper end to the water chamber or to the water tube 3, so 70 as in operation to form an essential part thereof. It is preferably of a size permitting a slight clearance 12^a between the tube 3 and the guard 12 and preventing any interference with the operation of the valve 75 5. In Fig. 1 the spring 12 is shown slightly extended, so that the spacing between the coils is increased and they are drawn closer to the tube than when in the normal condition of the spring, which latter is illustrated in Figs. 2 and 3. The gas generated in the carbid chamber 8 escapes upward through a filter pad 13 or equivalent part, and thence to a tube 14 and the burner 15.

As thus described the operation is as follows:—The water chamber 1 is charged with a suitable quantity of water through the capped inlet 2, the valve 5 being closed to prevent the escape of the water through the tube 3. The carbid chamber 8 is supplied 90 with a suitable quantity of carbid and secured in its seat upon the water chamber 1, the free end of the tube 3 protected by its guard 12 being located within the body of the carbid, in such manner, however, that 95 the rotation or movement of the valve will be in no way communicated to the carbid. Thus the carbid can in no way come in contact with the said valve, nor with the tube 3, being effectually kept therefrom by the 100 guard 12. The feed of the water to the carbid is effectively controlled by rotating the stem 6 by means of the screw threaded button 7 or a lever connected thereto, whereby the valve may be opened to the proper 105 extent to regulate the flame by the supply of water, which readily seeps through between the layers of the wire in the guard 12. In practical operation the water discharged from the tube is directed laterally 110

upon the upper surface of the valve, and is impinged thereby upon the juxtaposed encompassing portion of the guard, whence it rises in the space 12^a between the tube and the guard to quite an extent by capillary action and under the head maintained by the water in the reservoir 1, escaping between the proximate convolutions of the guard, which thus has a distinct distributing function. Due to this coöperation of parts, water is discharged from between the convolutions of the spring directly against the carbid in the upper part of the receptacle, as well as against that in the lower part, with the result that the slaking of the carbid progresses uniformly. Practical use of the device has demonstrated that this obviates the necessity of readjusting the water valve as the slaking of the carbid progresses, as it renders it unnecessary to depend upon the absorption of water by the upper portion of the carbid charge from slaked carbid in the lower portion of the receptacle about and below the discharge end of the water tube. In operations of the device it has been observed that when the valve is opened, water issues from between the coils throughout the extent of the guard substantially coincidentally. When the carbid is fully spent, the carbid chamber 8 is removed and the spent carbid is discharged, when the operation may be repeated. Any portion of the carbid adhering to the guard 12 is readily released by reason of the flexibility of the guard, it only being necessary to grasp the free end of the same and either bend it laterally slightly or elongate it slightly, and upon release, it will spring back to its normal position. In addition to this, practical use shows that when round wire is used in the guard, the slaked carbid does not readily adhere thereto, and the water passing through between the contiguous wires serves to operatively free the guard from the carbid. In the operation of inserting the tube into a container of fresh carbid, it and the valve are protected by the guard, and the guard itself is supported by the tube throughout substantially its entire length, so that it will not be deflected from the line of thrust and interfere with progress of the tube into the carbid.

Having thus described my invention, what I claim as new and desire to secure by Letters Patent is:—

1. In a carbid lamp the combination with a water receptacle and a carbid receptacle of a water discharge tube communicating with the former and extending into the latter, a guard mounted on said tube and extending substantially the entire length thereof and below the lower terminus thereof, said guard encompassing and being spaced from the wall of the tube to afford a channel for the progress of the water up said

wall, and having lateral water passages, the lower end of the tube having a water discharge orifice, and a valve operably arranged within the guard to close said orifice; said valve having a laterally extending surface arranged to conduct water from the tube toward the guard and having its periphery arranged in juxtaposition to the guard so as to impinge water thereon.

2. In an acetylene generating apparatus, the combination with a water container and a carbid container of a water discharge tube communicating with the former and extending a substantial distance into the latter, a flexible guard encompassing the tube and provided with lateral water passages, said guard extending throughout substantially the entire extent of the tube within the carbid container and depending below the lower end of the tube, said guard normally being spaced from the wall of the tube to afford a channel for the passage of water upwardly between the two, a valve operably arranged within the guard to close against the end of the tube and having a face extending transversely thereof in position to receive water from the tube, the periphery of said valve terminating adjacent the encompassing portion of the guard in position to impinge water thereagainst adjacent the end of the tube, and means for operating the valve.

3. In an acetylene generating apparatus, the combination with a water container and a carbid container of a water discharge tube communicating with the former and extending a substantial distance into the latter, an extensible guard encompassing the tube and provided with lateral water passages, said guard extending throughout substantially the entire extent of the tube within the carbid container and depending below the lower end of the tube, said guard normally being spaced from the wall of the tube to afford a channel for the passage of water upwardly between the two, a valve within the guard extending below the lower end of the tube and having a face extending transversely thereof in position to receive water from the tube, the periphery of said valve terminating adjacent the encompassing portion of the guard in position to impinge water thereagainst adjacent the end of the tube, and means for operating the valve.

4. In an acetylene gas generator, the combination of a water container, a carbid container, a water discharge tube communicating with the former and extending a substantial distance into the latter, a helical spring encompassing the tube for substantially its entire extent within the carbid container and depending below the discharge end of the tube, said spring normally being spaced from the wall of the tube to afford a channel for upward progress of water therebetween, and a water control member

disposed within the guard and coöperating with the lower portion of the tube and extending transversely thereof in position to receive water therefrom and direct it toward the encompassing portion of the spring, the periphery of said water control member lying adjacent encompassing coils of the spring in position to impinge water thereon adjacent the lower end of the tube, and

means for adjusting said water control member.

In testimony whereof, I have hereunto signed my name in the presence of two subscribing witnesses.

JACOB S. SHERMAN.
